UNITED STATES PATENT OFFICE.

EDWIN E. BARNEY, OF NEW ROCHELLE, NEW YORK, ASSIGNOR TO REMINGTON TYPE WRITER COMPANY, OF ILION, NEW YORK, A CORPORATION OF NEW YORK.

TYPEWRITING MACHINE.

Application filed January 27, 1923. Serial No. 615,202.

To all whom it may concern:

Be it known that I, EDWIN E. BARNEY, citizen of the United States, and resident of New Rochelle, in the county of Westchester 5 and State of New York, have invented certain new and useful Improvements in Type-writing Machines, of which the following is a specification.

My invention relates to typewriting or 10 like machines, and more particularly to small compact machines of the so-called portable class.

The objects of my invention, generally 15 stated, are to improve various features of such machines, as will hereinafter appear.

My invention consists in the features of 20 construction, arrangements of parts, and combinations of devices set forth in the following description and particularly pointed out in the appended claims.

In the accompanying drawings wherein like reference characters indicate corresponding parts in the different views,

Figure 1 is an enlarged fragmentary detail 25 left-hand elevation of the machine with parts in section, the section being taken on the line 1—1 of Figure 5, looking in the direction of the arrows at said line, and showing the parts as they appear when the machine is in condition for use.

Figure 2 is a fragmentary detail sectional view taken on the line 2—2 of Figure 1 and looking in the direction of the arrow at said line and with parts omitted.

Figure 3 is a like view of the same showing the parts disposed as they appear when the line spacing spindle is drawn out to the limit of its movement before the spindle is turned 180°, to enable it to be entirely withdrawn from the platen.

Figure 4 is a detail side view of the line spacing actuating member controlled by the line spacing spindle.

Figure 5 is a view corresponding to Figure 1 but showing the machine inclosed within its carrying case and conditioned for transportation.

Figure 6 is a fragmentary detail front elevation of the left-hand end of the carriage 50 and its support, with parts in section and parts omitted.

Figure 7 is a detail detached rear view of the line spacing spindle.

Figure 8 is a detail detached front view 55 of the same.

Figures 9, 10 and 11 are detail sectional views of the means for supporting the platen at the right-hand end thereof; Figure 8 being a section on the line 8—8 of Figure 10 and looking in the direction of the arrows at 60 said line, and Figure 9, a section on line 9—9 of Figure 8 and looking in the direction of the arrows at said line.

I have shown my invention in the present instance embodied in a Remington portable 65 machine, and from certain aspects the invention may be said to be in the nature of an improvement on features of construction of such machine disclosed in the application of Joseph B. Holden, Sr. No. 547,128, 70 filed March 27, 1922. It should be understood, however, that the invention is not restricted to embodiment in such machines, but may be employed wherever found available in typewriting or like machines. 75

Certain features of the construction disclosed in my present application are covered by claims contained in a co-pending application filed by me December 30, 1922, Sr. No. 610,057; the claims of the present application being restricted to features not disclosed in said previously filed case. 80

In the Remington portable machine, and as disclosed in said Holden application, the carriage as a whole is mounted on a support secured to a case shift frame, and a carriage center lock is employed to lock the carriage in a centered position in its line of travel on said support. This is to enable the close fitting cover of the case to be placed over the machine and locked in its closed position. A finger wheel for the platen of such machine is mounted for movement from a compact to an expanded position, and vice versa, and through intermediate 85 devices coacts with the center lock and the carriage release, and will prevent the cover from being placed on the machine unless the machine is properly conditioned to receive it. 95

By the present invention I provide an improved line spacing mechanism including an actuating finger piece, arm or handle that is 100

movable from a compact position to an expanded position for use, where it may be operated with greater facility. The spindle on which said finger piece is mounted co-acts with a center lock to maintain it effective or render it ineffective, depending on the longitudinal position of the spindle, and likewise to maintain the carriage free from restraint of its feed mechanism or enable the carriage to be held by its escapement mechanism, depending on whether the center lock is maintained effective or ineffective. I also provide means whereby the construction in question contributes to the ready removal of the platen when desired.

In the accompanying drawings I have shown only so much of the Remington portable machine as is necessary to arrive at an understanding of my invention in its embodiment therein. Such machine includes a frame 1 on which a carriage support 2 is mounted for fore-and-aft case shifting movement on parallel arms, one of the rear set of which is indicated by the reference numeral 3. The carriage support includes sheet metal guide rails 4 and 5 grooved to receive cross rollers 6 and 7 that bear on tracks 8 and 9 formed in the main sheet metal body portion 10 of the carriage. End plates 11 and 12 of the carriage are secured to and project upwardly from the member 10 thereof; one (11) at the left-hand end of the carriage, and the other (12) at the right-hand end thereof. A bearing member or bushing 13 is seated in an opening in the left-hand end plate 11 and is fixed therein by riveting the bushing at 14. The bushing has a central bearing opening to receive and form a bearing for a line spacing spindle or shaft 15 that extends through said bushing and into the platen head 16 and telescopes in the platen. The platen head is secured by screws 17 to the core 18 of a platen 19, whereas screws 20 secure a line spacing wheel 21 to the platen head 16. Within the core of the platen is mounted a bearing sleeve 22 in which the inner end portion of the spindle 15 receives a bearing. The outer end of the spindle has fixed thereto a finger piece or handle 23, which I prefer to make in the nature of a crank arm projecting from the spindle 15 and shaped somewhat as shown, for reasons which will hereinafter appear. The spindle 15 is formed with a spline groove 24, which, together with other details of construction of the spindle, will be herein-after more fully referred to. A hub of an actuating member 25, shown in detail in Fig. 4, is supported on the spindle 15 intermediate the end plate 11 and the platen head 16, as shown in Fig. 6. This head has an inwardly extending projection 26 that ordinarily extends into the spline groove 24 in the spindle to cause the spindle and hub to turn together and permit the spindle to move

longitudinally a limited distance independently of the hub. Projecting from the hub of the member 25 is a downwardly extending crank arm 27 for actuating the line spacing pawl, as will presently appear. This arm 70 27 co-acts with a projection 28 extending forward from a sheet metal lever or pawl-carrier 29 pivoted on a shouldered pivot screw 30 held on the end plate 11. The upper end of the lever 29 carries a pivot 31 75 on which line spacing pawl 32 is mounted, the hook-like engaging nose 33 of the pawl being adapted to engage the teeth 34 of the line spacing wheel 21. The line spacing pawl carries an offset integral projection 35 80 that normally rests on a regulating device 36 pivoted at 37 on the end plate 11. The adjustment of this regulating device determines the extent of line spacing movement transmitted to the line spacing wheel and 85 the platen, as pointed out in the patent to Herbert E. Bridgwater, No. 1,375,772, dated April 16, 1921. The lever 29 which carries the line spacing pawl, has a finger 38 bent to the left and then forwardly therefrom to 90 embrace the end plate 11 and assist in guiding the arm 29, and also to co-act with the end plate at 39 (see Fig. 1) to limit the movement of the lever 29 to normal position. The arm 29 is limited in its line spacing movement by an edge 40 of the offset 35 on the line spacing pawl co-acting with a contact edge 41 of the end plate 11. A spring 42 is coiled around the pivot screw 30 and bears at one end against the lever 29 to return it 100 to normal position.

The manner of mounting the left-hand end of the platen on the spindle 15 enables the platen and spindle to turn each independently of the other; although in the line 105 spacing operation a clockwise motion of the spindle, as the parts are viewed in Fig. 1, effects an anti-clockwise movement of the line spacing wheel and platen. Moreover, as hereinbefore indicated, the spindle 15 110 with the attached handle 23, may be moved axially from a compact position with the handle close to the carriage, as shown in dotted lines in Fig. 6, to the expanded position shown in full lines, where the handle 115 may be operated with greater facility. It will be seen from an inspection of this figure that when the handle is in the compact dotted line position, it may be received within the close fitting cover of the carrying case, one side wall *a* of which is indicated in dotted lines in this figure. On the other hand, when the handle and spindle are in the expanded full line position for use, the spindle will extend in the path of the 120 cover and prevent it from being placed in position. The cover, in addition to the side wall *a*, includes an opposite side wall *b*, a rear wall *c*, a top wall *d*, and a bottom wall or baseboard *e*.

The construction and arrangement of the parts, whereby the spindle 15 is enabled to be shifted from compact to expanded position for use; whereby the spindle may be prevented from being accidentally shifted from said last mentioned position; and whereby when desired the spindle may be manipulated so that it may be detached from the platen and permit the latter to be removed, will now be explained in detail. From what has been said, it will be understood that when the spindle 15 is in either the full or dotted line position shown in Fig. 6, the projection 26 on the line spacing actuating member 25 extends into the groove 24 in the spindle, forming a splined connection between the two, or a connection which causes the two to turn together but enables the spindle to be moved longitudinally independently of said actuating member. So long as the spline projection remains in the groove 24 in the spindle the latter is limited in its turning movement to less than 180° by reason of its operative connection with the line spacing devices. It will be seen that the groove 24 is closed at both ends; at one end by an end wall 43 of the groove and at the other end by a pin 44 fixed in the spindle. To the left of where this pin 44 is located, the spindle is formed with a circumferential groove 45 that extends entirely around the spindle and provides a laterally extending passage or channel at the inner end of the spline slot 24. On the opposite side of the spindle 15 from that which contains the spline slot or groove 24, is a short longitudinally extending slot 46 of a width sufficient to receive the projection 26 of the member 25, and extending to the right of the channel 45. The outer end of this slot 46 communicates with the passage 45 and the inner end terminates at the reduced inner or right-hand half of the spindle. In order to dismount or demount the platen it is necessary to entirely remove the spindle 15. To do this, it is necessary to first move the spindle out as far as the limits of the spline groove 24 will permit. This position is shown in Fig. 3, where it will be seen that the spindle has been moved longitudinally to the left until the pin 44 strikes the spline projection 26. The said projection is then in register with the cross channel or groove 45 in the spindle and the spindle is now free to be turned independently of the member 25 an unlimited distance. If, at this time, the handle 23 be turned forward through about 180°, the short slot 46 will be brought into register with the projection 26. If the spindle then be shifted longitudinally to the left, it may be entirely withdrawn from the platen and from the member 25 and the bushing 13, the projection 26 passing through the slot 46 as the spindle is

withdrawn. By reversing these movements, the parts in question may be readily assembled and operatively connected.

Any suitable means may be employed for detachably mounting the platen at the other end thereof, such, for example as the means disclosed in Figs. 9, 10 and 11, and which will be hereinafter described. These means are shown in my hereinbefore mentioned application filed Dec. 30, 1922, and are not claimed herein.

The various devices not yet referred to, which are affected by the spindle 15, and by which the spindle is locked against accidental longitudinal displacement from its position of use, will now be described. It will be seen that the bushing 13 is formed with a transverse slot 47 in the front side thereof and which extends about half-way through the bushing. There is also formed in the spindle 15 a corresponding transverse slot, notch or groove 48 that extends transversely therethrough about half-way at the front side thereof. When the spindle 15 is shifted longitudinally to its position for use, indicated in full lines in Fig. 6, these slots 47 and 48 are in register and are adapted to receive therein a locking latch, member or finger 49, as shown in Figs. 1 and 6. This prevents the spindle from being shifted longitudinally either outwardly or inwardly from the full line position shown in Fig. 6, but does not prevent an oscillation or limited turning movement of the spindle. From an inspection of Fig. 1 it will be seen that the finger 49, where it extends above the center of the spindle 15, slopes forwardly at 50 away from the bottom wall 51 of the slot 48 in the spindle. By reason of this fact a forward swinging motion of the handle 23 from the Fig. 1 position turns the spindle a limited distance in a clockwise direction as seen in this view, and the parts are moved back to normal position without affecting the member 49, or being interfered with by such member.

When the latch 49 is withdrawn from the slot 48 the spindle 15 may be shifted outwardly beyond its position for use, and then turned 180°, as hereinbefore explained, to withdraw the spindle and dismount the platen, or the spindle may be shifted in the opposite direction to the compact position, shown in dotted lines in Fig. 6. When shifted to this last position the full portion of the spindle at its greatest diameter crosses the slot 47 and the finger 49 is adapted to bear against such full portion of the spindle, as indicated in dotted lines in Fig. 5.

In the present instance, I have formed the locking finger as a part of a member, indicated as a whole by the reference numeral 52, and mounted to turn on a shouldered nut 53 threaded on the pivot screw 30

on the end plate 11. The member 52 is extended rearwardly where it is provided with a finger piece 54 that projects to the right, behind the usual carriage releasing arm 55, so that a forward movement of the finger piece 54, from the Fig. 1 to the Fig. 5 position, carries the arm 55 with it. The arm 55 is provided with a finger piece 56, whereby when desired the arm 55 may be moved to releasing position independently of the finger piece 54 and the member 52 which carries it. The arm 55 is fixed at its lower end by rivets 57 to a sheet metal angular plate 58 that extends throughout the length of the carriage and has a feed rack 59 riveted thereto, at 60. The plate or bar 58 has upwardly extending arms 61 pivoted at 62 on the carriage in the usual manner, and is moved forward to the normal Fig. 1 position by springs 63. The bar 58 is limited in its movement to and from normal position by the usual means, not shown in their entirety. In the normal Fig. 1 position, the teeth 64 of the feed rack engage a feed dog 65. At the down stroke of a printing key or the space key this dog is thrown out of engagement with the feed rack and the holding dog 66 is engaged therewith; the up-stroke of the key reversing the movements of the dogs and enabling the carriage to advance one step in the usual manner.

From the foregoing it will be understood that when the finger piece 54 is moved forward to release the locking finger 49 from the slot 48, it carries with it the carriage release arm or lever 55, as shown in Fig. 2, thereby disengaging the feed rack, and freeing the carriage from restraint of its escapement mechanism. This forward movement of the member 54 also controls the action of a carriage center lock, which may be of any suitable construction; that shown in the present instance being the same as the lock disclosed in my hereinbefore mentioned co-pending application, and which will now be described.

A forwardly extending projection or arm 67 on the member 52 projects over the free end portion of a locking member 68, which is in the nature of a leaf spring anchored at one end by a screw 69 to the body portion or plate 10 of the carriage. The free end of this spring is bent downwardly to form a locking projection 70 which registers with a slot 71 in the plate 10. The tension of the spring from which the member 68 is formed is exerted to return said member to and normally maintain it in the elevated position, shown in Figs. 1 and 6. A second locking member 72 in the nature of a leaf spring is anchored at one end by a screw 73 to the bottom of the carriage support. This locking member has an upwardly extending integral projection 74 which extends through a slot 75 in the carriage support and has

oppositely beveled edges 76 and an intermediate locking slot or recess 77. The tension of the member 72 is exerted to return it to and normally maintain it in the elevated position.

When the operator moves the finger piece 54 forward to the Fig. 2 position as described, the effect is not only to release the carriage and withdraw the locking latch 49 from the slot 48, but also to force the locking projection 70 down into co-operative relation with the companion locking member 72. The carriage at this time being free to travel, either moves under the power of its carriage spring to the left from an off-centered position, or is pushed to the right from an off-centered to a centered position, where it may be received within the cover of the carrying case. During this movement of the carriage the held-down projection 70 will co-act with one or the other of the cam or inclined edges 76, causing a depression of the member 72 until the projection reaches the locking notch 77 when the member 72 will spring up and bring about an interlocking engagement of the projections 70 with the opposite side walls of the notch 77. This occurs when the carriage is accurately centered in its line of travel and locks the carriage against movement in both directions, or to either right or left.

The movements of the parts described take place as a necessary preliminary to inclosing the machine in its carrying case. Thus, before the case can be closed it is necessary to move the line spacing handle to compact position. Before this can be done, the finger piece 54 is necessarily actuated as described to release the carriage and render the carriage center lock effective, at the same time withdrawing the locking latch 49 to release the line spacing spindle. The spindle may then be pushed in from the full to the dotted line position in Fig. 6. This results in bringing a full portion of the spindle into the path of the finger 49, which at this time will rest on the spindle when pressure is released on the finger piece 54, thereby locking the member 52 against return movement from its actuated position, as indicated in Fig. 5. It follows, therefore, that the locking projection 70 will be maintained indefinitely in its locked position and the carriage will be maintained indefinitely free from restraint of its escapement mechanism. When free the spindle 15 and its arm 23 are again moved to the full line position in Fig. 5, the latch 49 will spring into the locking slot 48 in the spindle, which slot at this time registers with the latch. The movement of the latch into said slot enables the member 52 to move back to the Fig. 1 position, thereby permitting the feed rack to re-engage the feed dog 65, and the projection 70 to be

withdrawn from the locking notch 77. The machine is then in condition for use, so far as the parts under consideration are concerned.

- 5 It will be understood from what has been said that a removal of the locking latch 49 from the slot 48 in the spindle 15 enables the latter to be moved outwardly beyond the full line position in Fig. 6, and permits 10 the finger piece 23 to be manipulated as hereinbefore described, to entirely withdraw the spindle in order that the platen may be dismounted and removed from the carriage.

The means for dismounting the platen at 15 the other end thereof, and which are shown in Figs. 9 to 11 inclusive, will now be described. The platen head 78 is fixed to the right-hand end of the platen by screws 79. The hub of the platen head is formed with 20 an inwardly projecting spline 80 received in a spline groove 81 of a spindle 82, to cause the platen and spindle to turn together but enable the latter to be shifted longitudinally relatively to the platen. The 25 outer end of the spindle has a finger piece or wheel 83 secured thereto. The inner portion of the spindle is received in a bearing sleeve 84 within the core of the platen, and also within the bearing opening in the platen 30 head. The spindle also extends through and receives a bearing in a bushing 85 seated in an opening in the end plate 12 of the carriage, and fixed in place therein by riveting the bushing at 86 (see Fig. 10) over a 35 washer 87, against which the hub of the platen head 78 is adapted to bear. The spindle is thus fixed to turn with the platen and receive its support in the bushing to sustain or support the platen in place. A 40 fore and aft vertical slot 88 is provided half-way through the bushing, the slot being bounded on one side by the end plate 12, and on the other side by the head 89 on the bushing, which is indicated in dotted lines 45 in Fig. 9. A detent 90, formed from spring wire and best shown in Fig. 9, comprises a curved portion 91 seated against a correspondingly curved portion of the bushing between the head 89 thereof and the end 50 plate 12, and a straight engaging portion 92 that is received in the slot 88 in the bushing. This engaging portion 92 is adapted to be seated in one or the other of two circumferential transverse grooves 93 and 94 55 in the spindle 82, and prevent an accidental longitudinal displacement of the spindle in either direction. The force of the spring of the detent 90 is exerted to retain the locking portion 92 thereof in the groove 93 or 94 in which it may be seated. To release the 60 detent, the upper end 95 is moved rearwardly, or to the left as the parts appear in Fig. 9, removing the locking member 92 from the groove 93 or 94 in which it is seated. While the detent is thus held the spin-

dle is moved slightly to bring an ungrooved portion thereof opposite the locking member 92. The detent may then be released and the spindle moved longitudinally until the other groove reaches the detent, when 70 the latter will snap into place in such groove and prevent further longitudinal movement of the spindle. When the spindle 82 and finger wheel 83 are in the expanded or full line position for use, as shown in Fig. 11, 75 the spindle is interposed in the path of the side wall *b* of the cover, shown in dotted lines, and will prevent the cover from being placed in position to inclose the machine. When, however, the finger wheel and 80 spindle 82 are moved to the contracted or compact dotted line position shown in Fig. 6, they may be received within the cover and no longer form an obstruction that prevents a closing of the cover. 85

By releasing the detent 90 and entirely withdrawing the spindle 82 from the platen and from its support in the end plate 12, the platen is relieved from all support at 90 the right-hand end and may be removed from the carriage after the left-hand spindle has been removed in the manner hereinbefore described.

The co-axially arranged spindles 82 and 15 may thus be caused to support the platen in place; may be shifted away from each other from contracted, or compact positions to expanded positions for use, where they prevent the machine from being inclosed within its carrying case until properly conditioned for this purpose; may be locked against accidental displacement in either direction from their positions of use; and may, when desired, be shifted outwardly beyond 100 said positions to disconnect them from the 105 platen and permit a removal of the latter from the machine.

From an inspection of Figs. 1, 5 and 6, it will be understood that the rear surface of the line spacing handle 23 with which the 110 fingers of the operator co-act, is in a plane at an angle of approximately 45° to the line of travel of the carriage; the handle is thus shaped so that the operator may conveniently return the carriage to the right and effect a 115 line spacing of the platen by one movement of the hand; such movement being exerted to the right on the handle as well as forwardly thereon.

Various changes may be made without departing from my invention as it is defined in the accompanying claims and certain features thereof may be employed without others.

What I claim as new and desire to secure by Letters Patent is:

1. In a typewriting or like machine, the combination of a platen, a spindle adapted to telescope in the platen and to be moved from a contracted position to an expanded position for use and having a transverse notch 130

or groove therein, a finger piece mounted on said spindle, a locking latch adapted to enter said notch and hold the spindle against longitudinal displacement in either direction, a line spacing pawl, and means controlled by a turning movement of said spindle for actuating said pawl.

2. In a typewriting or like machine, the combination of a platen, a spindle adapted to telescope in the platen and to be moved from a contracted position to an expanded position for use and having a transverse notch or groove therein, a finger piece mounted on said spindle, a locking latch adapted to enter said notch and hold the spindle against longitudinal displacement in either direction, a crank arm having a splined connection with said spindle, a line spacing pawl, and means controlled by said crank arm for actuating said pawl.

3. In a typewriting or like machine, the combination of a platen, an oscillatory line spacing spindle on which the platen is adapted to turn, said spindle being shiftable longitudinally from a contracted position to an expanded position for use, and means for limiting the extent of oscillation of said spindle when it is in position for use and for permitting the spindle to be turned beyond its points of limited oscillation when it is moved longitudinally beyond its position for use and only when thus turned permitting a withdrawal of the spindle from the platen to enable the latter to be demounted.

35. 4. In a typewriting or like machine, the combination of a platen, an oscillatory line spacing spindle on which the platen is adapted to turn, said spindle being shiftable longitudinally from a contracted position to an expanded position for use, means for limiting the extent of oscillation of said spindle when it is in position for use and for permitting the spindle to be turned beyond its points of limited oscillation when it is moved longitudinally beyond its position for use, and only when thus turned permitting a withdrawal of the spindle from the platen to enable the latter to be demounted, and releasable means for holding said spindle against accidental longitudinal displacement from its position for use.

5. In a typewriting or like machine, the combination of a platen, a spindle adapted to telescope in the platen and to be moved from a contracted position to an expanded position for use and having a transverse notch or groove therein, a finger piece mounted on said spindle, a locking latch adapted to enter said notch and hold the spindle against longitudinal displacement in either direction, a line spacing pawl, means controlled by a turning movement of said spindle for actuating said pawl, and a carriage center lock comprising a hand actuated member by which the center lock is rendered effective.

and when moved for this purpose releases the said locking latch to permit the spindle to be moved longitudinally.

6. In a typewriting or like machine, the combination of a platen, a spindle adapted to telescope in the platen and to be moved from a contracted position to an expanded position for use and having a transverse notch or groove therein, a finger piece mounted on said spindle, a locking latch adapted to enter said notch and hold the spindle against longitudinal displacement in either direction, a line spacing pawl, means controlled by a turning movement of said spindle for actuating said pawl, and a hand actuated means for releasing said locking latch and simultaneously freeing the carriage from restraint of its escapement mechanism.

7. In a typewriting or like machine, the combination of a platen, a spindle adapted to telescope in the platen and to be moved from a contracted position to an expanded position for use and having a transverse notch or groove therein, a finger piece mounted on said spindle, a locking latch adapted to enter said notch and hold the spindle against longitudinal displacement in either direction, a line spacing pawl, means controlled by a turning movement of said spindle for actuating said pawl, a carriage center lock comprising a hand actuated member by which the center lock is rendered effective and when moved for this purpose releases the said locking latch to permit the spindle to be moved longitudinally, and means by which the carriage is freed from restraint of its escapement mechanism when said hand actuated member is moved to release the locking latch.

8. In a typewriting or like machine, the combination of a platen, an oscillatory line spacing spindle on which the platen is adapted to turn, said spindle being shiftable longitudinally from a contracted position to an expanded position for use, means for limiting the extent of oscillation of said spindle when it is in position for use and for permitting the spindle to be turned beyond its points of limited oscillation when it is moved longitudinally beyond its position for use and only when thus turned permitting a withdrawal of the spindle from the platen to enable the latter to be demounted, and a hand releasable locking latch for holding said line spacing spindle against accidental longitudinal displacement from its expanded position for use.

9. In a typewriting or like machine, the combination of a platen, an oscillatory line spacing spindle on which the platen is adapted to turn, said spindle being shiftable longitudinally from a contracted position to an expanded position for use, means for limiting the extent of oscillation of said spindle when it is in position for use and for per-

mitting the spindle to be turned beyond its points of limited oscillation when it is moved longitudinally beyond its position for use and only when thus turned permitting a withdrawal of the spindle from the platen to enable the latter to be demounted, a hand releasable locking latch for holding said line spacing spindle against accidental longitudinal displacement from its expanded position for use, and a carriage center lock whose effectiveness and ineffectiveness is controlled by the actuation of said locking latch.

10. In a typewriting or like machine, the combination of a platen, an oscillatory line spacing spindle on which the platen is adapted to turn, said spindle being shiftable longitudinally from a contracted position to an expanded position for use, means for 20 limiting the extent of oscillation of said spindle when it is in position for use and for permitting the spindle to be turned beyond its points of limited oscillation when it is moved longitudinally beyond its position for use and only when thus turned permitting a withdrawal of the spindle from the platen to enable the latter to be demounted, a hand releasable locking latch for holding said line spacing spindle against 30 accidental longitudinal displacement from its expanded position for use, and means controlled by the act of releasing said locking latch for freeing the carriage from restraint of its escapement mechanism.

35. 11. In a typewriting or like machine, the combination of a platen, an oscillatory line spacing spindle on which the platen is adapted to turn, said spindle being shiftable longitudinally from a contracted position to an expanded position for use, means for 40 limiting the extent of oscillation of said spindle when it is in position for use and for permitting the spindle to be turned beyond its points of limited oscillation when it is moved longitudinally beyond its position for use and only when thus turned permitting a withdrawal of the spindle from the platen to enable the latter to be demounted, a hand releasable locking latch for holding said line spacing spindle against 45 accidental longitudinal displacement from its expanded position for use, a carriage lock for locking it in centered position in its line of travel, and means controlled by the act of releasing said locking latch for rendering said carriage lock effective and for simultaneously releasing the carriage from restraint of its escapement mechanism.

60. 12. In a typewriting or like machine, the combination of a platen, a spindle therefor, means for preventing the spindle from being withdrawn from the platen except at one position to which the spindle may be turned, means for preventing the spindle from being turned to such position until it is first

moved longitudinally to a given point, and releasable means for preventing said spindle from being accidentally moved longitudinally to said given point.

65. 13. In a typewriting or like machine, the combination of a platen, a spindle therefor, means for preventing the spindle from being withdrawn from the platen except at one position to which the spindle may be turned, means for preventing the spindle from being turned to such position until it is first moved longitudinally to a given point, releasable means for preventing said spindle from being accidentally moved longitudinally to said given point, a carriage lock for locking the carriage in a centered position in its line of travel, and means controlled by said releasable means for controlling the effectiveness of said carriage lock.

70. 14. In a typewriting or like machine, the combination of a platen, a spindle therefor, means for preventing the spindle from being withdrawn from the platen except at one position to which the spindle may be turned, means for preventing the spindle from being turned to such position until it is first moved longitudinally to a given point, releasable means for preventing said spindle from being accidentally moved longitudinally to said given point, and means controlled by said releasable means for freeing the carriage from restraint of its escapement mechanism.

75. 15. In a typewriting or like machine, the combination of a platen, a spindle therefor, means for preventing the spindle from being withdrawn from the platen except at one position to which the spindle may be turned, means for preventing the spindle from being turned to such position until it is first moved longitudinally to a given point, releasable means for preventing said spindle from being accidentally moved longitudinally to said given point, a carriage lock 80 for locking the carriage in a centered position in its line of travel, and means controlled by said releasable means for rendering the carriage lock effective when said releasable means are released and for simultaneously freeing the carriage from restraint of its escapement mechanism.

85. 16. In a typewriting or like machine, the combination of a longitudinally shiftable and turnable line spacing spindle having in one of its sides a longitudinally extending groove with closed ends and lateral openings at one point in its length and also having in another side a longitudinally extending groove open at one end and having lateral openings which communicate with the lateral openings in the first mentioned groove, and a line spacing pawl actuating member, supported on said spindle and having a spline projection that may be received 90

in said grooves and lateral openings depending on the relative position of the spindle to said actuating member, whereby with the spindle in one position it and the actuating member are connected to turn together and in another position of the spindle it may turn relatively to said actuating member and be detached therefrom.

Signed at the borough of Manhattan, city of New York, in the county of New York and State of New York, this 25th day of January, A. D. 1923.

EDWIN E. BARNEY.
